UNITED STATES PATENT OFFICE.

LUKE E. MURPHY, OF MILWAUKEE, WISCONSIN.

SHOE.

Application filed April 25, 1922. Serial No. 556,523.

To all whom it may concern:

Be it known that I, LUKE E. MURPHY, a citizen of the United States, and resident of Milwaukee, in the county of Milwaukee and State of Wisconsin, have invented certain new and useful Improvements in Shoes; and I do hereby declare that the following is a full, clear, and exact description thereof.

The invention relates to shoe fasteners.

Hitherto, in the lacing of shoes, difficulty has been experienced with the eyes which are spaced in marginally from the edge of the upper by reason of the manner in which the lace lies thereunder. The inner crossings 10 of the lace result in unusual thickness at places adjacent the eyes and this bunching proves uncomfortable and creates an irregularity that is displeasing to the eye. Similarly with the hooks, their being spaced inwardly from the edge results in an angling or up-setting 15 of the hook gromet by which the hook is secured to the shoe being displaced slightly from the surface of the ankle so that the result is uncomfortable.

The invention comprises a plurality of 20 eyes and hooks secured by means of gromets to the edge of the shoe upper, the hooks and eyes being spaced laterally marginally from the edge so that the shoe upper does not extend beneath the hooks and eyes. Thus the 25 lacing does not at any place overlie the leather of the shoe, but extends between the edges and over the tongue.

A primary object of the invention is the 30 prevention of the cutting action by bunched lace, which results from the structure wherein the eye is spaced inwardly in a marginal manner and the elimination of tendency of the hooks to angle. This renders the shoe 35 more comfortable to the foot and gives it a more pleasing appearance as the surface is substantially smooth. There is very little frictional resistance to the movement of the shoe lace, which is received in the metallic 40 eyes and hooks and has very little superficial contact with the leather. This permits the lace to be readily tightened on the ankle and makes for ready adjustability of the lace so that the upper accommodates itself to the 45 movement of the foot of the wearer.

An object of the invention is the provision 50 of such structure as will have the foregoing advantages and yet be adapted to any style of lacing, permitting the lace to be readily inserted into the eyes without loss of time.

An object of the structure is, also, strength. The fact that the hooks and eyes are substantially in the same plane as the gromets which secure them to the shoe upper tends to eliminate tendency of the 60 gromet to tear loose as the force exerted thereon is not in a direction at an angle to the plane in which the gromet lies, but is substantially in the same plane with the gromet.

With the above and other objects in view, which will appear as the description proceeds, my invention resides in the novel construction, combination and arrangement of parts, substantially as hereinafter described 70 and more particularly defined by the appended claim, it being understood that such changes in the precise embodiment of the herein disclosed invention may be made as come within the scope of the claim.

In the accompanying drawing, I have illustrated one complete example of the physical embodiment of the present invention constructed according to the best mode I have so far devised for the practical application of the principles thereof, and in which:

Figure 1 is a front elevation of a shoe provided with the novel hooks and eyes, and

Figures 2 and 3 are sections substantially 85 on the lines 2—2 and 3—3, respectively, of Figure 1.

The shoe is provided with uppers 10 provided with lining 11 at the edges of which is positioned narrow reinforcing bands 12. 90 Hooks 13 terminate in gromets 14 directed through reinforcements 12 and lining 11 and lying substantially in the same plane as the hooks. The hooks are spaced slightly from the edges of the upper inwardly and may be 95 of any desired number, four of them being shown in the embodiment illustrated. The ends 15 of the hooks are spaced slightly from the body portion 16 thereof, so as to permit the free entry of the lace 17, which may be 100 readily positioned therein and withdrawn. The lower part of the shoe has a series of pairs of spaced eyes 18 secured by body portions 19, substantially in the manner in which hooks are secured to reinforcements 105 12 and lining 11. The eyes are, also, spaced laterally from the edges of the uppers and may be of any desired number. Their dimensions are such as to permit the ready insertion and free movement of lace 17 there- 110

in, and the hooks and eyes are substantially aligned so that the lace may be readily threaded through the hooks and eyes and tensioned to draw the upper closely about the ankle.

5 This movement is unimpeded by frictional contact of lace 17 with the leather. Lace 17 does not overlie any part of the shoe except tongue 20, which contacts with lining 11 and is spaced over gromets 14 in such wise as to prevent the metal thereof from biting into the flesh of the wearer. As both hooks and eyes are in substantially the same plane as the gromets, by which they are secured to the shoe upper, the tensioning of lace 17 10 does not result in any angling of the gromet with respect to the surface of the foot. The fact that lace 17 does not at any point underlie the edges of the front of the shoe prevents a bunching along the edge and 15 eliminates irregularities, the edge of the shoe being substantially of uniform thick- 20

ness from top to bottom and lying perfectly smooth along the foot. The free movement of lace 17 in the metallic eyes and hooks permits the shoe to adjust itself readily to diverse positions of the foot and at all times the structure is entirely comfortable and ornamental.

I claim:—

The combination of a shoe upper having 30 a pair of spaced flies formed of an outer and an inner ply, a series of opposed hooks projecting into the space between the flies and having shanks positioned between the plies, and securing means extending through the 35 shanks and through the inner ply and covered by the outer ply.

In testimony that I claim the foregoing I have hereunto set my hand at Milwaukee, in the county of Milwaukee and State of Wis- 40consin.

LUKE E. MURPHY.
